UNITED STATES PATENT OFFICE.

CECIL M. WINBIGLER, OF WASHINGTON, DISTRICT OF COLUMBIA.

GAME.

Application filed January 31, 1924. Serial No. 689,740.

To all whom it may concern:

Be it known that I, CECIL M. WINBIGLER, a citizen of the United States, residing at Washington, District of Columbia, have invented certain new and useful Improvements in Games, of which the following is a specification.

My invention relates to a game to be played on a small game board together with the necessary apparatus, and has been designed and studied with the purpose of visualizing a game of golf as nearly as possible. Inasmuch as golf is played without constant reference to yardage, and is rather a question of experience and trial with a large element of chance involved in every stroke, so this game has been designed with that idea in view. From every position on a golf course, many possibilities confront the player before making a stroke, both in distance and direction, and the various clubs used in playing the game of golf are not arbitrarily confined to certain limited distances or to any clear line of direction. I have designed this invention taking into account the major possibilities from every position indicated on a golf course.

In my invention, the course is laid out to some convenient scale and every position has likewise been paid off to the same scale so that the game as played visualizes the distances of the various shots in relation to the scale of the course.

The board is suitably colored and drawn to give a picture of an actual golf course and every hole is shown in its correct length, with the topography, foliage, hazards, etc. to further visualize the game. The course is shown in its entirety in order that the player can better follow the progress of play around the entire nine holes represented.

The arrangement of the holes have been presented as shown in order to facilitate easy progress from hole to hole as the game is played. A different arrangement of these holes would be necessary on a different shaped board, but would not alter the method of playing the game as hereinafter set forth.

Every game of this character must use some method to replace the actual striking of a ball with a club, so it is provided that dice should be used or any other chance control device which gives the results necessary

for the progress of the game. Dice are preferred inasmuch as they provide the means of keeping the game moving rapidly and thereby increase the interest of the player.

To further describe the game, it will be necessary to refer to the various drawings which accompany and form a part of this specification.

In the drawings:—

Fig. 1 is a plan view of a golf course used as a playing board upon which the game is played, and represents an actual playing board, which is laid out to some convenient scale;

Fig. 2 is an enlarged view of the first hole;

Fig. 3 is a view in perspective of a holder used to engage the cards;

Fig. 4 is a perspective view showing the cards mounted on the holder;

Fig. 5 is a view in perspective of the marker used upon the playing board;

Fig. 6 is a perspective view of different colored chips of any suitable material, which are to be used as counters in playing the game;

Fig. 7 is a perspective view of a pair of dice;

Fig. 8 is a detailed view of the face of the card for the first hole;

Fig. 9 is a detailed view showing the back of the card for the first hole;

Fig. 10 is a detailed view of that part of the card for the second hole which departs from the information or arrangement already shown on the card for the first hole;

Fig. 11 is a detailed view showing that part of the card for the third hole which departs from the information or arrangement already shown on the card for the first hole;

Fig. 12 is a detailed view showing that part of the card for the fourth hole, which departs from the information or arrangement already shown on the card for the first hole;

Fig. 13 is a detailed view showing that part of the card for the fifth hole which departs from the information already shown on the card for the first hole;

Fig. 14 is a detailed view showing that part of the card for the sixth hole, which departs from the information or arrangement already shown on the card for the first hole;

Fig. 15 is a detailed view showing that part of the card for the seventh hole, which departs from the information or arrangement already shown on the card for the 5 first hole;

Fig. 16 is a detailed view showing that part of the card for the eighth hole, which departs from the information or arrangement already shown on the card for the 10 first hole;

Fig. 17 is a detailed view showing that part of the back of the card for the seventh hole which departs from the information or arrangement already shown on the back of 15 the card for the first hole, and provides for the continuation of the shots necessary to complete the eighth hole;

Fig. 18 is a detailed view of that part of the face of the ninth hole, which departs 20 from the information or arrangement already shown on the card for the first hole;

Fig. 19 is a detailed view showing that part of the back of the card for the eighth hole which departs from the information or 25 arrangement already shown on the back of the card for the first hole, and provides for the continuation of the shots necessary to complete the ninth hole;

Fig. 20 is a diagrammatic illustration of 30 a method of presenting the information contained on these cards on a scroll of paper.

The playing board illustrated in Fig. 1 is 35 suitably colored in different shades of green, the rough, fairways and putting greens are in distinct shades of green. The putting greens are indicated by a flag and pole, the tees are numbered. The board contains the following notations at the places indicated:

a, Top Ball; b, Slice; c, Hook; d, Short 40 Drive; e, Rough; f, Long Drive; g, Top Ball (2); h, Short Iron; i, Long Iron; j, Top Ball (3).

At each location on Fig. 1, there is also 45 noted the club which should be used to get the best results from that particular location. These notations, in reference to the clubs, however, do not play a part in the game itself, but are valuable in teaching the beginners the proper club to use in the different positions represented.

The above is better illustrated in Fig. 2, 50 which is an enlarged view of the first hole and shows the actual notations indicated on the board for the first hole in their correct positions.

The illustration, Fig. 3, is a view in perspective of the holder used to engage the cards and is a very cheap and simple device 55 stamped out of a single piece of metal and bent to shape as shown in the illustration. The part of the holder indicated by the letters k and l are the two legs supporting the holder; the back rests indicated by m and n are bent up and back to provide the back 60 supports against which the cards rest when

mounted on the holder. The tongue or part represented by o is bent into a circular contour as illustrated. The upper portion of this tongue forms a lip which is bent into a groove at p in which the cards set when 70 mounted on the holder, see Fig. 4. Fig. 4 shows the cards mounted on the holder and indicates the position of these cards after they have been placed in position. The cards are slipped over the free end of the 75 tongue o into the groove p by means of the hole q shown punched in the cards. The cards are then in correct position resting against the backs m and n.

The card is also illustrated in position 80 after being turned down. The hole q easily passes over the tongue o and the card assumes the position illustrated resting against the leg k.

The marker illustrated in Fig. 5 is also 85 stamped out of a small piece of metal and represents a golf player holding a golf club in the position of addressing a golf ball before making a shot. The base r in size exactly fits the tees for the various holes, as 90 illustrated at 1 in Fig. 2, and is modeled and colored to represent turf.

Four markers are provided, one for each 95 player, and in order to differentiate them, the sweater coat indicated by the letter S, shown on the figure is colored to match the chips. It is to be understood, however, that the number of players may be less than four. In fact, the number of players that engage in the game is immaterial.

The chips illustrated in Fig. 6 are colored as indicated, red, white, blue and yellow. Twelve chips are provided for each 105 player. The player places a chip on the board for every stroke taken on any hole. Each hole is in reality a small individual game, so the chips are removed from the board at the end of each hole.

The dice illustrated in Fig. 7 are different from ordinary dice in so far as the 110 markings are concerned. A pair of dice is provided for each player. Fig. 7 illustrates every face of the dice. It will be noted that the numeral 6, ordinarily represented on dice, is replaced by an O, as indicated on the face marked t.

The foregoing description covers the apparatus used in playing the game with the exception of the cards shown in Figs. 8, 9, 10, 11, 12, 13, 14, 15, 16, 17, and 18 accompanying this specification. An additional explanation of these cards will be an aid in understanding the game. The cards, nine in number with one additional card containing general instructions making ten in all, provide all the information for playing the game. These cards are punched at the bottom with an aperture q to fit the tongue marked o on the holder, see Fig. 3, and are shown mounted on the holder in Fig. 4 of 125 130

the drawings accompanying this specification. As the cards are turned down in the holder, all the information for play for any one hole is presented to view. This is 5 graphically illustrated in Figs. 8 and 9, the upper card Fig. 8 contains all the information necessary for play between the tee marked 1 and the putting green of the first hole, see Fig. 2.

10 The lower card, see Fig. 9, contains all the information necessary for play on the putting green. This arrangement of the information on these cards is the same for all holes or throughout the entire set of cards, 15 thereby making available all necessary information for each hole as that hole is being played.

The numbers on the cards tie up with the numbers on the dice, see Fig. 7, and call for 20 certain shots, see Fig. 8, which in turn are indicated by the drawing representing the playing board or notations contained thereon, see Figs. 1 and 2.

25 Referring again to Fig. 8, it is proposed to print these cards in three colors, an olive green background, red for all shots indicated in double line letters, and black for all other shots.

It will be noted that Figs. 17 and 19 represent the backs of the cards for the seventh and eighth holes, and that there is more information shown here than is provided for on the backs of the cards for the other holes. The backs of the cards for the seventh and 35 eighth holes contain, in addition to the putt schedule, one or two other shots. As the cards are turned in the holder, the back of the card for the seventh hole contains the putt schedule for the following hole, or the eighth hole. The same is true of the putt 40 schedule for the ninth hole contained on the back of the card for the eighth hole.

The eighth and ninth holes are long holes 45 and therefore require more shots to reach the greens. For this reason, it is necessary to carry some of the shots for play between the tee and green over to the backs of the cards containing the putt schedule for these holes or the preceding cards.

50 The arrangement of information as shown on the face and back of the cards, see Figs. 8 and 9, is the same for all other holes, in so far as the division between fairway and green is concerned.

55 Referring again to Fig. 8, it will be seen that all shots follow in regular logical order. The first shot is always a drive for holes two hundred yards or over; a penalty shot or bunker shot is next provided and is shown in red. This shot is for players who are in trouble after the drive. The next shot is the approach shot, known as such because the player when taking this shot is within shooting distance of the green. The last shot provided is a short approach shot com-

monly known as a chip shot, this shot is for distances immediately surrounding the green.

It will be noted on these cards that penalty shots, consisting of brook shots, top ball 70 shots and bunker shots, are indented, all other shots carry out to the same line on the cards.

This has been done to more clearly indicate these penalty shots. No penalty is attached to bunker shots not indicated in red, because the average player can as a rule successfully play a short shot out of a bunker. The bunkers having no penalties are in the immediate neighborhood of the greens. 75

Inasmuch as it is possible to present the information shown on the cards of this game in a different way and still secure the same results, it is proposed to also present the information in another way, i. e., printed 80 on a scroll of paper and operated on two rollers or cylinders. To better illustrate this method of presentation, reference to Fig. 20 in the drawings accompanying this specification will show a scroll of paper indicated by the letter *u* wound upon two rollers *v* and *w*, the rollers to turn in opposite directions. The information contained on the scroll can be brought to view as the rollers are turned forward or backward. It 85 is proposed to operate these rollers and scroll of paper in a suitable holder, and read the information through a window opening or openings in the holder.

The cards presented in Figs. 8 to 19 inclusive could readily be bound together into a small book and used in that way. This, however, would not alter the method of play or depart from the spirit of this invention. 90

In my invention I have tried to present the information as nearly uniform as possible, in order to facilitate ready reference as the game is being played. The information as presented is so easily read and easily 95 remembered that it is possible after playing the game two or three times to practically ignore the cards and refer to them only in case of doubt. For that reason, a game played as outlined above more nearly approaches the actual conditions existing on a 100 golf course.

There are two main numerical divisions noted on the cards, i. e., odd and even numbers. The odd numbers in nearly all cases 105 are poor shots and the even numbers are good shots. By dividing the numbers in this way, it is possible to balance the chances more satisfactorily in relation to the conditions under which the various shots are 110 made, thereby securing a better balanced game. The penalty provided on the cards for 00 under drive, see Figs. 8, 11, 13, 14, 15, 16 and 18, and first iron shot 115 in Figs. 10 and 12, remains the same for all 120 125 130

succeeding shots, unless otherwise indicated. In all cases this shot changes under chip shot on the cards of all the various holes, and again under putt in the putt schedule.

5 The game contains only one special rule as far as the game of golf is concerned, and it is rarely necessary to call this rule into force. The rule has to do with the bunker shots shown entirely in red; and provides 10 that any player who fails to get out of a bunker after two trials will add one additional chip or stroke to his or her score and place marker on the fairway just clear of the bunker, then proceed to the next shot 15 on the card.

In designing the putt schedule, it was deemed advisable to limit the number of possible putts to four, inasmuch as it is rarely necessary for a player to take more 20 than four putts on any green when actually playing golf. The putt schedule is therefore divided into two parts, i. e., first and second putt and third putt. If the player does not hole out in his first two putts on the 25 green, the player will then take the third putt indicated on the card, which provides for holding out in one or two additional putts.

The playing board in appearance closely 30 resembles an actual golf course, and due to the method of playing the game, it is possible to keep the few direction markings on the board, subordinate to the picture. In selecting the information for the cards, 35 recognized golf terms have been used and a beginner playing this game can readily become familiar with them as this game is being played. The easy reference provided by the cards speeds up the game and avoids 40 the necessity of making any calculations whatsoever.

Having briefly described the apparatus necessary for playing this game, the method of play will possibly be an aid in understanding the game.

Inasmuch as this is a game of golf, the rules of golf apply.

Four people or even five players can conveniently play this game at one time.

50 Let us assume that four people are playing the game; in golf terms, this would be designated a foursome; three people playing together are a threesome, two a twosome, and one a single.

55 Before play is started, each player is provided with a marker as shown in Fig. 5, and twelve chips (see Fig. 6) in color corresponding with the color of the marker.

60 For convenience, we will designate the players A, B, C and D, and assume that A and B are partners and C and D are partners. This provides for match play between these two sets of partners, and it would also be possible at the same time to provide 65 for medal play between the different play-

ers as individuals. We will assume that A and B have won the honor or the right to drive first from the tee of the first hole, and further assume that A of the partners A and B is the first to drive.

70 The rules of the game provide that before taking a shot, the player will place a chip upon the board, this will be so for all shots taken during the progress of the game. Reference should be made to Fig. 2 of the 75 drawings. A will place his marker on the tee of the first hole, then, after chipping up, will roll the dice, which upon coming to rest show a 1 and 4. Referring to card Fig. 8 under drive, it is seen that 5 calls for bunker 80 so to right. A will then place marker in the bunker to the right, see Fig. 2. All players when taking the tee shots will tee up markers before driving. B is the next to drive, after chipping up, B's dice indicate 2 and 4. Reference to card Fig. 8 under drive, shows short drive. B will then place marker at short drive, see Fig. 2. Having teed up, 85 C is the next to drive, after placing a chip on the board. C's dice indicate 2 and 1. Reference to card for the first hole under 90 drive, it is found 3 indicates top ball bunker. C will place marker at top ball, see Fig. 2. Player D, having teed up, is the last to 95 drive. After placing a chip on the board, D's dice come to rest showing 3 and 1. Reference to card for first hole under drive, it is found D has a long drive. D will place marker at long drive, see Fig. 2.

Now all the players have driven, and are 100 in the following positions on the board, see Fig. 2: A is in the bunker to the right, B is at short drive, C is in the bunker at top ball, and D is at long drive. You will notice that 105 A and C unfortunately made the bunker on their drives, or, referring to the card, Fig. 8, A and C played a red shot. It is, therefore, necessary under the rules of this game for these players to next play a red shot, or the bunker shot, as shown on the 110 card, see Fig. 8. Under the rules governing play in an actual game of golf, the player who is farthest away from the hole in the putting green, is always the next to shoot. C is away. Therefore, C will be the first to 115 take the next shot. After chipping up, C's dice show a 3 and 4. Referring to the card, Fig. 8 under bunker shot, we find that C is still in the bunker. C is, therefore, still 120 away, so will shoot again. After chipping up, C's dice show a 5 and 4. Reference to card Fig. 8 under bunker shot, we find that C is out in the rough to the right. C will 125 place marker in rough indicated to right beyond the bunker. See Fig. 2. A, being away, will now shoot. After chipping up, A's dice show 2 and 4. Referring to card Fig. 8, under bunker shot, it is seen that A is out at long drive. A will, therefore, place marker at long drive. See Fig. 2. B is 130

now away, having made a short drive, and will be the next to shoot. After chipping up, B's dice show a 5 and 2. Now B was not in trouble on the drive, therefore, will skip the bunker shot and take the next shot indicated on the card, see Fig. 8, which is the approach shot. It will be noted that 7 calls for a shot, short of the green. B will place marker on the board short of the green, see Fig. 2. C is now away, being in the rough to the right. After chipping up, C's dice show a 4 and 4. Reference to the card Fig. 8 under approach shot, C is on the green, and will not shoot again until all players are on the green. Assuming that player D is away, it will be noted that D has not taken a shot since the drive. After chipping up, D's dice show 0 and 5. Referring to card Fig. 8 under approach shot, D is over the green. D will place marker over the green, see Fig. 2.

A is now away. After chipping up, A's dice show 0 and 2. Referring to card under approach shot, Fig. 8, it will be noted that A is on the green. B is now away. After chipping up, B's dice indicate 4 and 1. Reference to card Fig. 8, it will be noted that B having taken the approach shot, will not take the chip shot. Under chip shot, 5 calls for a dub shot. B has dubbed a shot and must repeat. The chip shot provided on the card being the last shot before reaching the green, all players not on the green after the approach shot and one chip shot will repeat the chip shot until on the green. After chipping up, B's dice show 5 and 3. Referring to card Fig. 8, it will be seen that B is on the green.

D is now the only player not on the green. After chipping up, D's dice show 3 and 3. Referring to card Fig. 8, D is on the green. All players are now on the green. Reference should now be made to Fig. 9, which provides for all necessary shots on the putting green and is shown on the back of every card. In that way the putt schedule is available for every hole being played, as the cards are turned down in the holder, see Figs. 3 and 4.

Assuming that A is away from the cup; A will now putt. After chipping up, A's dice show 2 and 1. Referring to card Fig. 9, it will be seen that A has missed the putt. For convenience in expediting the game, A will again putt. After chipping up, A's dice show 5 and 1. Referring to card Fig. 9, it is found that six is holed out in two putts. That makes three putts for A. A must place an additional chip in the board, this completes A's score for the first hole. B is the next to putt. After chipping up, B's dice show 4 and 2. Referring to card Fig. 9, B has holed out in two putts. B will place an additional chip on the board. This completes B's score for the first hole. C is the

next to putt. After chipping up, C's dice show a 4 and 3. Referring to card Fig. 9, it is seen that C has holed out.

D is the last to putt. After chipping up, D's dice show 6 and 5. Referring to card Fig. 9, D is short of the cup. D will putt again. After chipping up, D's dice show 3 and 0. By reference to card Fig. 9, it is seen that D has missed the putt. D will putt again; having taken two putts, D will now take the third putt shown on the card, see Fig. 9. After chipping up, D's dice show 4 and 3. By referring to the card, it will be seen that D has holed out. Counting the chips in front of the players, we find that A has 6, B has 6, C has 5, and D has 6, so that C has won the hole. Now A and B had the honor on the tee of the first hole, but C of the partners C and D having won the hole, the honor now passes from A and B to C and D. Therefore, C and D will take the first shot from the tee of the second hole.

The method of play indicated above is characteristic for all holes. The cards, as well as the shots for the various holes, follow in regular order as progress is made from the tee to the green. When the last hole is played, the cards are then turned down. By simply turning them up in the holder, the game is ready to be played again.

Referring to Fig. 1, it will be noted that an additional hazard has been added in the nature of a brook running through the fairways of holes 2, 4, 7 and 8. The penalty for shooting into the brook is the addition of one stroke. That is, the player will lift ball from the brook and drop back, adding a penalty stroke for so doing. The penalty provided for 00 on the cards is a lost ball. This penalty for 00 remains the same for all shots except chip shots and putt. It will be noted that the penalty 00 is indicated in the first shot on all the cards. The general instructions for the game provide that the conditions for 00, as indicated under the first shot on every card, remain the same for all shots, unless otherwise indicated. If the player loses a ball, he will add one stroke to his score by placing an additional chip on the board, and will repeat the shot from the same position, adding an additional chip for the repeated shot.

It would be proper at this point to say a word about the actual game of golf in its relation to the game above described.

In playing golf, little or no attention is paid to yardage, except in so far as it is used as a basis for calculating the par for each hole of the course. The player is always endeavoring to make scores as near par as possible and trial and experience are the best teachers to determine the possibilities of the different clubs he carries in his bag. These clubs, in his hands, are at times productive of the most exceptional shots and at

other times the results are most disappointing. There is always the big element of chance involved whenever a stroke is taken; this is especially so with the average player, and this game has been designed to represent the play of the average player. However, it is possible to play par and under par on the course presented in my game if the player's luck is running strong. The balancing of chances in my invention, being the relation of the information on the cards to the combination of numbers on the dice, has been carefully worked out to secure as nearly as possible the conditions actually existing on a golf course, at the different positions indicated. The chips provide a very convenient method of keeping score.

It will be noted after a study of the cards, that the player's chances of reaching the green constantly increase as he approaches the green. In playing the game in competition, no hole is safely won until all players have holed out; there is always the possibility of one or more of the players holing out a short approach shot, or chip shot. After reaching the green, there is always the possibility of the player with the lowest score, taking several putts and the player with the higher score taking a lesser number of putts and winning the hole. It will be seen after a little study of the cards in my game, that these conditions are provided for.

No penalties have been provided for play in the rough, this is so because, on most well kept golf courses, the chances of making good shots in the rough are almost equal to the chances on the fairway; this is especially so at certain seasons of the year. Many of the best shots made on a golf course are made from the rough, due to the fact that the player is making a special effort at that time, because of the handicap.

Every golf course differs in the character of its rough, depending on the policy of the management and the amount of money available for keeping the course in condition. On most courses the rough is the same turf as the fairway, only not cropped as close.

50 I claim:—

1. In a game such as described, and in combination, a playing board representing a complete golf course separate, cards for each hole having indicia thereon representing the shots for each hole, and chance means for obtaining the data for each shot.

2. In a game such as described, and in combination, a playing board with direction markings indicated thereon, indicia having information co-related to the information on the playing board, chance means co-operating with said indicia for indicating each shot, and counters for keeping a record of the number of strokes taken by the players as the game progresses from hole to hole.

65 3. In a game such as described, and in

combination, a playing board representing a complete golf course separate, cards for each hole having indicia thereon representing the shots for each hole, and chance means cooperating with said indicia immediately indicating each shot. 70

4. In a game such as described, and in combination, a playing board with direction markings indicated thereon, cards having information co-relating to the information on the playing board, dice for throwing to select the information, and chips to be used as counters for keeping a record of the number of strokes taken by the players as the game progresses from hole to hole. 75

5. In a game such as described, and in combination, a playing board with direction markings indicated thereon, cards having information thereon co-related to the markings on the playing board, dice for throwing to select the information, and various colored chips to be used as counters for keeping a record of the number of strokes taken by the players as the game progresses from hole to hole. 80

6. In a game such as described, and in combination, a playing board representing a complete golf course, cards having indicia thereon representing the shots for each hole, a marker to be used for each shot to be 95 taken by a player, chance means for obtaining the data for each shot, and counting means for keeping a record of the number of strokes taken by the players as the game progresses from hole to hole. 90

7. In a game such as described, and in combination, a playing board representing a golf course, indicia representing the shots for each hole, a marker for each player, chance means cooperating with said indicia immediately indicating each shot, and counting means for keeping a record of the number of strokes taken by the players as the game progresses from hole to hole. 105

8. In a game such as described, and in combination, a playing board representing a complete golf course, cards having indicia thereon representing the shots for each hole, a marker for each player, chance means for obtaining the data for each shot and chips 110 to be used as counters for keeping a record of the number of strokes taken by the players as the game progresses from hole to hole. 115

9. In a game as described, and in combination, a playing board representing a complete golf course, markings on the course indicating the type of stroke and club to be used, cards having indicia thereon representing the shots for each hole, and chance means for obtaining the data for each shot. 120

10. In a game as described, and in combination, a playing board representing a complete golf course, markings on the course indicating the type of stroke and club to be used, cards having indicia thereon repre- 125

senting the shots for each hole, and chance means cooperating with said indicia immediately indicating each shot.

11. In a game as described, and in combination, a playing board representing a complete golf course, markings on the course indicating the type of stroke and club to be used, cards having indicia thereon representing the shots for each hole, a marker representing the figure of a player to mark the position of each player, and chance means cooperating with said indicia immediately indicating each shot.

12. In a game as described, and in combination, a playing board representing a complete golf course, markings on the course indicating the type of stroke and club to be used, cards having indicia thereon representing the shots for each hole, a marker representing the figure of a player for each player, and dice for selecting the indicia on the cards whereby the shot is immediately indicated.

13. In a game such as described, and in combination, a playing board, indicia representing the shots for each hole, said indicia being divided between the several shots, and means provided whereby the penalty shots are displayed distinctively from the other shots.

14. In a golf game such as described, and in combination, a playing board, indicia representing the shots for each hole, the shots being indicated in rotation, means for distinguishing the penalty shots from the other shots both by color and position.

15. In a game as described, and in combination, a playing board representing a complete golf course, markings on the course indicating the type of stroke and club to be used, indicia representing the shots for each hole, and chance means cooperating with said indicia immediately indicating each shot.

In testimony whereof I affix my signature.
CECIL M. WINBIGLER.
